ARTIFICIAL TOOTH

Simon Myerson, Brookline, Mass.

Application December 20, 1937, Serial No. 180,725
Renewed June 14, 1939

9 Claims. (Cl. 32—9)

This invention pertains to artificial teeth or tooth facings of the kind wherein the incisal part at least of the tooth proper, for a substantial distance above the incisal edge, is wholly of a ma-

5 terial which transmits light more readily than does the central body and gingival portion of the tooth, thereby very closely simulating natural teeth, as described in the copending applications of Simon Myerson, Serial No. 78,674, filed May 8,

10 1936, and Serial No. 104,039, filed October 5, 1936.

In anchoring an artificial tooth or tooth facing in place, for example to a bridge, it is customary to employ a metallic supporting member. The facing element of the tooth may be secured to

15 this supporting member by means of a key-to-keyway joint and cementation, or by means of a pin or pins with or without solder. In plate-work it is usual to terminate the supporting member at a substantial distance from the incisal portion of the tooth, and under such circumstances the arrangement specifically disclosed in the aforesaid copending applications is desirable and adequate, since there is nothing at the lingual side of the incisal portion of the tooth to modify the desired

20 effects resulting from the transparency of such edge. However, for certain uses it is desirable to extend the backing or supporting member down substantially to the incisal edge, for instance, to reinforce the edge portion of the tooth.

25 30 When a backing of opaque material (for example metal) is thus extended down to the incisal edge, the color of the backing, for instance yellow gold, may seriously impair, if not wholly nullify, the advantages derived from the use of the transpar-

35 ent edge material.

One object of the present invention is to provide an artificial tooth, or a facing member therefor, having the incisal edge portion of a material which transmits light more readily than the central body portion of the tooth and wherein the backing extends substantially to the incisal edge, but having provision for so masking the effect of the backing member as substantially to preserve or at least to simulate the beneficial effects

40 45 which are normally obtained by the use of an unbacked incisal edge of translucent or transparent material.

Natural teeth are not of uniform color nor are the incisal edge portions of natural teeth (consisting almost wholly of enamel) exactly uniform in color, thickness or texture. As a matter of fact, the labial surface, and in particular the incisal portion of a natural tooth usually has narrow, more or less parallel, darker lines or stains

50 55 extending substantially perpendicular to the in-

cisal edge, that is to say, lengthwise of the tooth. These narrow lines usually result from the presence of fine cracks in the enamel.

A further object of the invention is to provide a tooth or a tooth facing such as may be manufactured in finished form by mass production methods and which is so constructed that, when viewed against the dark background of the oral cavity, it exhibits narrow streaks or shadow lines closely simulating those of natural teeth, the streak-forming material being a permanent part of the tooth structure incorporated during manufacture.

Other and further objects and advantages of the invention will be pointed out in the following more detailed description and by reference to the accompanying drawing, wherein

Fig. 1 is a front or labial elevation of an artificial anterior tooth embodying features of the present invention, the tooth being shown to very large scale;

Fig. 2 is a section substantially on the line 2—2 of Fig. 1;

Fig. 3 is a section substantially on the line 3—3 of Fig. 1;

Fig. 4 is a fragmentary section, to larger scale, on line 4—4 of Fig. 1;

Fig. 5 is a view similar to Fig. 1, but having portions of the tooth broken away to show the internal construction;

Fig. 6 is a view similar to Fig. 2, but illustrating a modification;

Fig. 7 is a perspective view, to very large size, illustrating an elongate piece of material such as may be employed to produce a striation in the tooth; and

Fig. 8 is a view similar to Fig. 2 but illustrating a different form of tooth and backing member.

Referring to the drawing, the numeral 1 designates the central or body portion of the tooth or tooth facing, such body portion being made of the usual ceramic material and having its front or labial surface 2 covered with enamel 3. As indicated in Fig. 2, this enamel extends down to a point well below the extreme lower edge 1a of the opaque body portion to form the incisal edge 4, the rear or lingual face 5 of this downwardly directed mass of enamel being of appreciable vertical extent, for instance, one-sixth or more of the total depth of the tooth. The enamel also extends laterally, as shown at 6 and 7 (Fig. 1), to points above the extreme lower edge 1a of the body portion, thus providing an incisal marginal portion of substantial depth consisting wholly of enamel. This enamel is of a material which

transmits light much more freely than does the material of the body portion 1, and thus below the lower end of the body portion there is a distinct area of substantial depth which is quite 5 translucent or even transparent.

The facing member (comprising the body portion 1 and the enamel) is secured, as shown in Fig. 2, by means of a pin 11 to a supporting member 8 which may be of any suitable and/or usual 10 material. As shown in Fig. 2, the supporting member 8 extends from the gingival surface 9 of the tooth down to the point 10, with its lower edge substantially flush with the incisal edge 4 of the tooth facing. Since the body of enamel at 15 the incisal edge is of substantial vertical depth, as indicated at 5, the lower part 10 of the supporting member would be more or less visible through this transparent incisal margin of the tooth and would thus impart its own color or 20 appearance to the lower portion of the tooth were some means not taken to prevent it.

In accordance with the present invention, and in order to prevent this undesired color effect of the supporting member material, a masking layer 25 12 is interposed between the body portion 1 and the supporting member 8. This masking layer 12 is of any suitable material having the desired characteristics, for example a layer of very opaque ceramic material. This layer 12 preferably 30 is secured to the tooth (comprising the parts 1 and 3) to form an integral portion thereof, and its color or other physical characteristics are such that when viewed through the transparent incisal margin of the tooth, substantially the same effect 35 results as though a tooth of this type, but without the support 8, were viewed against the dark background of the oral cavity. To obtain this effect, this layer 12 is preferably of some neutral shade, for example gray, and in order that it may be of 40 high light-dispersive and absorptive quality, thus to avoid reflection from its forward surface, it is preferred, as shown in Fig. 5, to give the labial face of this layer 12 a mat surface 12a.

While it may be more simple to have the masking layer 12 extend over the entire lingual surface of the tooth facing, it may, under some circumstances, be preferred to limit the layer 12 substantially to the exposed lingual surface of the transparent enamel 3 where the latter projects beyond the lower edge of the body portion 1. Thus, as illustrated in Fig. 6, wherein the tooth facing is shown as united to the support 8x by a key 11x and keyway 11y, the layer 12b of masking material covers only the surface 5 of the enamel, 55 while at the upper part of the tooth the support 8x contacts directly with the rear surface of the body portion of the tooth.

In Fig. 8 the invention is illustrated as embodied in a tooth of somewhat different form from that of Figs. 1, 2 and 3—the labial face of the tooth having angularly disposed faces for engagement by corresponding surfaces of a metallic supporting member 8a, to which the porcelain portion of the tooth is secured by means of a pin 11a. Interposed between the vertical part 10a of this metal plate and the transparent incisal margin of the tooth is a masking layer 12c of a material similar to that of the layer 12 above described.

70 In accordance with the present invention, it is also proposed to form the front or labial surface of the tooth so as even better to simulate a natural tooth by the inclusion of narrow streaks and stains of a color or appearance which visually contrasts with that of the enamel and simulates

the stains and streaks common in natural teeth. With this object in view, the present invention contemplates the use of elongate inserts 13 (Figs. 1 and 4) of a material less transparent than the enamel 3 and which may be deeply colored, these inserts being so disposed as to extend up from the incisal edge of the tooth to any desired distance and in general substantially perpendicular to such edge. As illustrated in Fig. 1 these inserts may extend upwardly beyond the lower edge of the body portion so that the upper part of the insert is in front of the body portion and projects forwardly from the latter into the layer of enamel which overlies the labial surface of the body portion. The intended effect of these inserts, at least at the translucent incisal portion of the tooth, is dependent upon the presence of a dark background (for example the oral cavity, or a proper masking for the supporting member) against which to view the more or less transparent incisal portion of the tooth. 10 15 20

In order to obtain the most desirable effects, it has been found that these inserts 13 should have very narrow forward edges 14, preferably approaching a knife edge in sharpness and 25 that these edges should preferably lie substantially in the plane of the outer surface of the enamel. Preferably these inserts 13 take the form of elongate, triangular prisms, desirably of slightly irregular contour so as better to simulate 30 the irregular striations of the natural tooth. As already stated, these inserts 13 contrast visually in appearance with the enamel; for example, they may be made of deeply colored material or a material which differs in opacity from the 35 enamel, and one or more of such inserts may be embedded in the enamel of the tooth so as to become fused or otherwise permanently integrated with the enamel, the operation of embedding the inserts in the enamel-forming material during the 40 packing of the tooth mould producing narrow, elongate grooves, crevices or fissures extending forwardly toward the labial surface of the enamel layer, and which are completely filled by the inserts. 45

If desired, the inserts 13 may be of a color different from that of the body portion 1 and, by making them of triangular contour, a more or less indistinct or shadow effect is produced which seems more closely to simulate the natural tooth 50 than though the insert be of uniform thickness. However, it is contemplated that inserts of other than triangular transverse section may be employed if desired. For convenience in description and in the claims reference has been made to 55 the upper and lower parts of the tooth, the tooth illustrated in the drawing having its gingival surface uppermost, but it is to be understood that such use of the terms "upper", "lower" etc. is merely relative and that the invention is not in 60 any way limited to teeth positioned as specifically shown in the drawing.

While I have herein disclosed certain desirable embodiments of the invention by way of example, it is to be understood that the invention is not 65 necessarily limited to these precise embodiments but is to be regarded as broadly inclusive of any and all equivalent arrangements whereby the improved results are obtained.

I claim:

1. An artificial tooth of the kind having a body portion of relatively opaque material which constitutes the major part of the tooth, a mass of relatively transparent enamel constituting the incisal portion of the tooth and terminating at 70 75

the incisal edge, and a supporting member disposed at the lingual side of the body portion and which extends downwardly to the incisal edge, characterized in that the incisal portion extends 5 downwardly below the lower end of the body portion to a distance such as to provide a light-transmitting area of substantial depth which would appear darker than the body of the tooth if viewed from the front against the background 10 of the oral cavity, and further characterized in having light-absorbing and diffusing means interposed between the supporting member and said light-transmitting incisal portion, said light-absorbing and diffusing means being gray in color 15 so as to impart substantially the same effect, as would the darkness of the oral cavity, to the transparent material of the tooth when the latter is viewed from the front.

2. An artificial tooth of the kind having a body 20 portion of relatively opaque material which constitutes the major part of the tooth, a mass of relatively transparent enamel constituting the incisal portion of the tooth and terminating at the incisal edge, and a supporting member disposed at the lingual side of the body portion and which extends downwardly to the incisal edge, characterized in that said mass of enamel has an upward extension overlying the lower part at least of the labial surface of the body portion, the 25 enamel mass extending down below the lower end of the body portion a distance substantially exceeding the maximum front-to-rear thickness of said upward extension, and further characterized in having interposed between the support and the 30 lingual surface of the relatively transparent incisal portion a layer of ceramic material of a neutral color and having a mat-finished labial surface operative to absorb and diffuse light falling thereon thereby to conceal the support and 35 simulate the effect of the darkness of the oral cavity when the tooth is viewed from the front.

3. An artificial tooth of the kind wherein a body portion of relatively opaque material is provided with an incisal portion of relatively 40 transparent enamel extending down below the lower edge of the body portion and wherein a supporting member is united to the body portion and extends downwardly to a point substantially flush with the incisal edge of the tooth, characterized in having means masking the backing material, said masking material being interposed between the supporting member and incisal margin and being of a character to simulate the darkness of the oral cavity when viewed through the 45 incisal portion, and means embedded in the incisal portion designed and arranged to simulate the relatively opaque striations and stains commonly occurring in the incisal portion of a natural tooth.

4. An artificial tooth of the kind having a body portion of a relatively opaque material and having its labial surface of a relatively transparent enamel which is fused to and which extends down below the lower edge of the body portion 50 to form an incisal margin of the transparent material, and an elongate, narrow, relatively opaque insert embedded in and fused with the enamel forming said incisal portion, said insert being initially separate, preformed and distinct from the body portion and enamel layer and being of 55 substantially wedge-shape in transverse section and having a very thin labial edge substantially flush with the labial surface of the enamel, said insert increasing in width rearwardly from the 60 labial surface of the enamel.

5. An artificial tooth of the kind having a body portion of relatively opaque material having fused to its labial surface a layer of relatively transparent parent enamel which continues down below the lower edge of the body portion and merges with 5 an incisal mass of enamel, and an elongate preformed narrow insert of ceramic material embedded in and fused with said enamel, said insert being initially separate and distinct from the body portion and enamel layer and having a thin 10 forward edge, one end portion at least of said insert being fused to and projecting forwardly from the body portion of the tooth, said insert increasing in thickness rearwardly from said edge and contrasting in appearance with that of 15 the enamel, the thin forward edge of the insert being substantially flush with the labial outer surface of the enamel thereby to produce the effect of a stria at the labial face of the tooth.

6. An artificial tooth of the kind in which the body portion has a layer of enamel fused to its labial surface, characterized in having a preformed elongate narrow insert of a material which differs in optical properties from the enamel layer embedded in and fused with said enamel layer, said insert being initially separate and distinct from the body portion and enamel layer and having a thin forward edge substantially flush with the outer surface of the enamel thereby to produce the effect of a stria at the outer 30 surface of the tooth.

7. An artificial tooth of the kind having a body portion of relatively opaque material which constitutes the major part of the tooth, and a mass of relatively transparent enamel constituting the 35 incisal portion of the tooth and terminating at the incisal edge, said enamel mass extending up toward the gingival surface of the tooth to form a labial surface layer which is fused to the body portion, characterized in that said incisal mass 40 of enamel extends downwardly below the lower end of the body portion to a distance such as to provide a light-transmitting area of substantial depth which appears darker than the body of the tooth when viewed from the front against 45 the background of the oral cavity, and further characterized in having an elongate preformed insert of ceramic material, initially separate and distinct from the body portion and enamel, which extends lengthwise of the tooth and which is 50 embedded in and fused with said enamel, said insert having a thin forward edge which is substantially flush with the outer surface of said enamel, the insert being of a distinctive visual appearance contrasting with the enamel thereby to 55 produce the effect of a stria at the labial face of the tooth.

8. An artificial tooth of the kind in which the body portion has a layer of enamel fused to its labial surface, characterized in having an elongate insert embedded in said enamel layer, said insert differing in optical properties from the enamel layer and being of substantially triangular transverse section with one acute longitudinal edge thereof disposed substantially in the labial surface of the enamel layer and with its lateral faces diverging rearwardly from said edge within the substance of the enamel whereby light which enters through the enamel is reflected toward the observer with varying effect from surfaces of the 70 insert which are inclined to the labial face of the tooth, said enamel, insert and body portion being interfused with each other.

9. In combination in an artificial tooth, an enamel layer having a concave lingual face and a 75

convex labial face, said enamel layer being designed to constitute the labial, mesial and distal surfaces of the artificial tooth, and an elongate separate and distinct insert of ceramic material differing in optical properties from the enamel layer and designed to simulate one of the longitudinal stria commonly occurring in natural teeth, said insert being embedded in the concave face of the enamel layer and fused with the enamel, the insert being substantially wedge-

shape in transverse section with its acute forward edge substantially flush with the labial surface of the enamel layer and with its lateral faces diverging rearwardly within the substance of the enamel whereby light which enters through the enamel is reflected toward the observer with an intensity which progressively decreases laterally from said edge of the insert. 5
